UNITED STATES PATENT OFFICE.

WILLIAM W. TUCK, OF RICHMOND HILL, AND AUGUST WASSMANN, OF ASTORIA, NEW YORK, ASSIGNORS TO ABBOT AUGUSTUS LOW, OF BROOKLYN, NEW YORK.

IGNITER FOR HYDROCARBON-ENGINES.

SPECIFICATION forming part of Letters Patent No. 716,314, dated December 16, 1902.

Application filed December 18, 1901. Serial No. 86,356. (No model.)

To all whom it may concern:

Be it known that we, WILLIAM W. TUCK, residing at Richmond Hill, and AUGUST WASSMANN, residing at Halletts Point, Astoria, Queens county, and State of New York, citizens of the United States, have invented certain new and useful Improvements in Igniters for Hydrocarbon-Engines, of which the following is a specification sufficient to enable others skilled in the art to which the invention appertains to make and use the same.

Our improvements relate to means for effecting the preliminary heating of an igniter in the combustion-chamber operated by the combustion or explosion of hydrocarbon, as in the ordinary and well-known form of so-called "gas-engines."

The novelty resides in the peculiar construction and arrangement of parts, as herein-after more fully described and claimed.

In the accompanying drawings, Figure 1 is a sectional elevation of the upper portion of a gas-engine cylinder and combustion-chamber, showing diagrammatically and symbolically the electrical connections. Fig. 2 is a horizontal section upon plane of line 2, 2, Fig. 1.

C represents the cylinder of any ordinary gas-engine, in which reciprocates the usual piston P. I is a globular ignition-chamber, the lower portion of which consists of an extension i' of the cylinder-head i and the upper portion of a cap i^2 , bolted to the lower section. It is obvious that the form and construction of the ignition-chamber I is of secondary importance, since our ignition-plate may be used in connection with various types of gas-engines.

As shown in the drawings, the ignition-plate A is flat and circular in general outline, being formed with two extensions a a' , which pass through insulating-plugs b , inserted in the lower section i' of the ignition-chamber.

The outer ends of these extensions a a' are connected electrically with the electrical circuit E, in which a battery e or other source of electricity is interposed, so that when the circuit is closed a current of electricity will

pass through the ignition-plate A sufficient to raise said plate to a temperature equal to the point of ignition of the hydrocarbon used,

which is injected into the ignition-chamber I and against the ignition-plate A by any suitable or well-known means, as through an injector B. (Shown symbolically in Fig. 2.)

The current is maintained until a sufficient number of charges have been fired to thoroughly heat the parts, when the circuit may be broken, the succeeding explosions thereafter being relied upon to maintain the requisite ignition temperature.

We prefer to form our ignition-plate A with a series of holes a^2 for the purpose, primarily, of increasing the superficial area exposed to the action of the hydrocarbon spray or vapor, thereby facilitating and perfecting combustion. Incidental in this connection the openings a^2 lighten the structure.

What we claim as our invention, and desire to secure by Letters Patent, is—

1. The combination with the ignition-chamber of a gas-engine, of an ignition-plate disposed centrally within said chamber, with its outer edge substantially concentric with the walls of said chamber and having integral extensions passed through insulated openings in the opposite walls of said chamber, and electrical connections with the outer ends of said extensions, substantially as and for the purpose specified.

2. The combination with the ignition-chamber of a gas-engine of globular form in sections, the lower section forming an extension of the cylinder-head with flanges, and the upper portion being a cap with coincident flanges, the lower portion being formed with openings in its opposite walls, insulating-plugs inserted in said openings, a flat substantially circular perforated ignition-plate disposed within said chamber with its edge substantially concentric with the walls of the chamber and formed with divergent integral extensions held in and passed through said plugs, by which the plate is supported in position, and electrical connections with the ends of said extensions, all substantially as and for the purpose specified.

WILLIAM W. TUCK.
AUGUST WASSMANN.
